United States Patent Office

Des. 185,649
Patented July 7, 1959

185,649

DRINKING GLASS OR SIMILAR VESSEL

Peter Schlumbohm, New York, N.Y.

Application May 2, 1957, Serial No. 45,990

Term of patent 14 years

(Cl. D36—8)

The figure is an elevational view of a drinking glass or similar vessel, showing my new design.

I claim:

The ornamental design for a drinking glass or similar vessel, as shown in the accompanying drawing.
